UNITED STATES PATENT OFFICE

2,101,268

ENVELOPE MACHINE

Abraham Novick, Flushing, N. Y., assignor to F. L. Smithe Machine Co., Inc., New York, N. Y., a corporation of New York

Application April 27, 1932, Serial No. 607,738

Renewed July 11, 1936

4 Claims. (Cl. 271—46)

This invention relates to envelope making machines, and has for an object to provide a timing and aligning mechanism which will be accurate and dependable.

The practice has been followed in the past of depositing envelope blanks separately and successively upon a stationary support and of providing timing and aligning pins carried by endless chains for engaging the trailing ends of the blanks at the junctions of the side flaps with the trailing central flap, and pushing the blanks forward to timed operating instrumentalities while subjecting the blanks to a frictional retarding influence.

The procedure outlined above has the drawback that in high speed machinery the pins come into engagement with a stationary blank while traveling at high speed. The inertia of the blank and the drag of the frictional retarding device interfere with the instantaneous acceleration of the blank to the speed of the pins. As a consequence, it is not uncommon for the pins to make dents or deformations in the trailing edge of a blank, which deformations preclude the proper alignment of the blank. In accordance with the present invention, provision is made for overcoming this difficulty.

To this end provision is made in accordance with a preferred embodiment of the invention of an auxiliary pin feeder, the auxiliary feeder pins traveling outside of, and at a little slower speed than, the main feeder pins. The pins of the auxiliary feeder are timed to engage the blank in advance of the pins of the main feeder, but to be overtaken by the latter and to give up control of the blank to them after the blank has been set in motion. In this way the impact of the main feeder pins against the blank is caused to be very light, since the blank is traveling at nearly the speed of the main feeder pins at the time when it is first engaged by them. Whether or not the blank is deformed by the auxiliary feeder pins is unimportant, since these pins engage portions of the blank which are not relied on for timing or aligning. Accurate timing and aligning are reliably accomplished by the pins of the main feeder.

Other objects and advantages will hereinafter appear.

In the drawings forming part of this specification,

Figure 1 is a view in sectional, side elevation of a portion of an envelope machine embodying features of the present invention, the section be-

ing taken on the line 1—1 of Figure 6, looking in the direction of the arrows;

Figure 2 is a fragmentary, detail, sectional view, the section being taken on the line 2—2 of Figure 6, looking in the direction of the arrows;

Figure 3 is a detail, vertical, sectional view taken on the line 3—3 of Figure 6, looking in the direction of the arrows;

Figure 4 is a diagrammatic, plan view illustrating the relation of the main and auxiliary feeders at the time when the auxiliary feeder pins first engage a blank;

Figure 5 is a view similar to Figure 4 illustrating the relation of the main and auxiliary feeders after the blank has been overtaken by the main feeder;

Figure 6 is a fragmentary, plan view showing the aligning and timing mechanism illustrated in Figure 1;

Figure 7 is a view similar to Figure 6, but showing certain of the parts broken away for the purpose of revealing underlying parts;

Figure 8 is a detail, plan view, partly broken away, illustrating features of the mounting of the main and auxiliary feeder mechanism at the adjustable side thereof.

The machine comprises a blank separating and feeding mechanism 1 of the type illustrated in Letters Patent of the United States to Charles F. Pflanze, No. 1,385,468. The envelope blanks are stacked upon a shelf 2 and are taken off one by one in timed relation by the separating and feeding mechanism referred to. Such mechanism comprises a feeding disc or cylinder 3 which carries a pair of friction feet 4. A shoe 5 stands in opposed relation to the cylinder 3 and to the friction feet 4, while a feed roller 6 is provided in position to cooperate with the cylinder 3. This mechanism is effective to deliver the blanks one by one in spaced relation and substantially in definitely timed relation onto a stationary table comprising relatively adjustable table members 7 and 8, and a plate 9 which is disposed between the table members 7 and 8. Bars 10 are disposed above the plane of the plate 9 and are provided with spring members 11 for bearing against the blanks to exert a frictional retarding influence on said blanks. Provision is made of an auxiliary feeder for starting the blanks into motion, which feeder comprises chains 12 and 13 that carry pins 14 and 15. Provision is also made of a pair of timing and aligning feeders which comprise chains 16 and 17 and pins 18 and 19. The chains 12 and 13 travel a little slower than the chains 16 and 17, but are so timed that a pair

of pins 14 and 15 engages the blank ahead of a pair of pins 18 and 19. This condition is illustrated in Figures 1, 4 and 6. The timing and relative speeds of the main and auxiliary feeders are such, however, that a pair of pins 18, 19 will overtake the blank and move it out of engagement with the pins 14, 15 before the blank has reached the ends of the active stretches of the chains 12 and 13. This condition is illustrated in Figure 5.

The spacing between successive pins 18, 19 of chains 16, 17 is slightly greater than the spacing between the pins 14, 15, respectively, of chains 12, 13, the relation of the spacing being as 10 is 15 to 9. The sprockets 38 and 17b by which chains 16, 17 are driven are larger in diameter than the sprockets 41 and 13b which drive the chains 12, 13, the ratio of the diameters of these sprockets being also 10 to 9. By reason of this, the 20 speed of chains 16, 17 is greater than the speed of chains 12, 13, namely, in the proportion of 10 to 9. The pins are so positioned on their respective sets of chains that the slower moving pins 14, 15 engage the blank slightly in advance 25 of the engagement thereof by the faster moving pins 18, 19, as indicated diagrammatically in Figure 4. By reason of the spacing and relative speeds of the above sets of pins, this condition will be repeated each time a blank is delivered from the hopper to the chains for alignment. The shafts 24 and 25 on which the sprockets for the two sets of chains are mounted are rotated at constant speed and at the same number of revolutions per minute.

35 It will be understood that the proportions above given are approximate and that wide variations may be made in practice from the values above given.

The machine includes a frame comprising side 40 members 20 and 21 for supporting the table members 7, 8, the plate 9, the chains 12, 13, 16 and 17, and the driving means for the chains. A cross bar 22 spans the space between the frame members 20 and 21 and is fixedly connected 45 to said members. Shafts 23, 24 and 25 also extend across the machine and are journaled in the side members 20 and 21. The shaft 24 has a bevel gear 26 fixed upon a reduced portion thereof. The chains 12 and 13 of the auxiliary feeder are driven through bevel gear 26 and shaft 24. The shaft 25 has a bevel gear 27 fixed upon a reduced portion thereof. The chains 16 and 17 of the main feeder are driven through bevel gear 27 and shaft 25.

50 A longitudinally extending bracket 28 is fixedly mounted upon the cross bar 22 and rests upon, interfits with, and partially surrounds hub portions of sprockets 17a, 13b and 17b, fixed respectively upon the shafts 23, 24 and 25. The bracket 28 has fixed upon arms 28a thereof a plate or block 29 having track grooves formed therein for supporting and guiding the chains 13 and 17. The bracket 28 also supports the table member 8 and a strip 30 of the table. The bracket member 28 is not laterally adjustable, but is fixed on the cross bar 22, and hence fixes the positions of the feeder chains 13 and 17 laterally of the machine.

A shaft 31 extends across the machine and is 70 journaled in the side frame members 20 and 21. The shaft 31 passes through the bracket 28 and has collars 32 fixed upon it at opposite sides of said bracket, so that the shaft is held against longitudinal movement. The shaft 31 is provided 75 with polygonal ends 33 so that a wrench may be

applied at either end of the shaft to rotate it. The shaft 31 has a threaded portion 34 which is effective to adjust the table 7 and the feeder chains 12 and 16 laterally of the machine. A bracket 35 is slidingly mounted on the cross bar 5 22. The bracket 35 extends longitudinally of the machine. The threaded portion 34 of the shaft 31 has screw engagement with members 36 fast on the bracket 35. Rotation of the shaft 31 in one direction is effective to carry the bracket 10 35 toward one side of the machine, while rotation of the shaft 31 in the opposite direction is effective to carry the bracket away from such side of the machine. The bracket 35 interfits with the hub portion 37 of a sprocket 38 whereby the chain 16 is driven. The hub 37 is moved longitudinally of shaft 25 by adjustment of the bracket 35. The hub 37 is rotatable with the shaft 25, rotation being effected through a key connection, the keyway being indicated in dotted lines at 39 in Figure 7. The bracket 35 similarly interfits with the hub portion 40 of a sprocket 41 which drives the auxiliary feeder chain 12. The sprocket is adjustable longitudinally of the shaft 24 by adjustment of the bracket 35, but is connected to be driven by the shaft 24 through a key 42 carried by the hub 40 and a keyway 43 that extends longitudinally of the shaft.

The bracket 35 also surrounds a reduced sleeve portion 44 of a sprocket 45 which is mounted upon shaft 23 and which has driving connection with the shaft by means of a key 46 carried by the sprocket and a keyway 47 formed in the shaft. The chain 16 runs upon the sprocket 45. 30

A sprocket 48 is journaled upon the reduced sleeve portion 44 of sprocket 45 and is held in bearing engagement with the outer face of the bracket 35 by means of a collar 49 made fast upon the sleeve portion 44. The sprocket 48 40 turns freely upon the sleeve portion 44 and the chain 12 of the auxiliary feeder runs upon the sprocket 48. It will be seen that adjustment of the bracket 35 laterally of the machine is effective to adjust chains 12 and 16 in unison without disturbing the operative relation of such chains to the means for driving them.

A track member 50 is fixed upon the bracket 35 and provides trackways for the chains 12 and 16. Table member 7 is mounted upon out-reaching arms 51 of the bracket 35 and upon the track member 50. A strip 52 of the table is also mounted upon the track member 50. The center plate 9 is fixedly mounted upon a center bracket 53, and the bracket is adjustably secured 55 in place upon the cross bar 22 by means of a set screw 54 and a lock nut 55.

The bracket 35 includes an arm 56 having a vertical slot 57 therein. A guide roller or sprocket 58 for the chain 16 is journaled upon the shank of a bolt 59 that extends through the slot 57. The bolt 59 is adjustable along the slot 57 and may be secured in place by means of a washer 60 and a nut 61 to maintain the chain 16 under the desired degree of tension. Provision 65 is similarly made on the bracket 28 for guiding the chain 17 and maintaining it under the degree of tension desired.

At the delivery end of the chains 16 and 17 the envelope blanks pass over a pair of rollers 70 62, 63 across a table 64. The blanks pass thence between feed rolls 65 and 66 across a table 67 and between rolls 68 and 69 which constitute a scoring couple. From the scoring couple 68, 69 the blanks pass to other instrumentalities for 75

completing the manufacture of them into envelopes.

I have described what I believe to be the best embodiment of my invention. I do not wish, however, to be confined to the embodiment shown, but what I desire to cover by Letters Patent is set forth in the appended claims.

I claim:

1. In an envelope machine, in combination, a table, a feeder for accelerating a blank on the table from a state of rest, said blank having re-entrant corners in its trailing edge comprising a pair of endless chains and pins carried by the chains and engageable with the trailing edge of the blank to initiate its forward movement, said pins engaging said blank at points other than said re-entrant corners, and a timing and aligning feeder operated at a higher speed than the first mentioned feeder, and comprising a pair of endless chains and pins on the chains for overtaking the blank, engaging the trailing edge thereof gently in said re-entrant corners, and taking over control of the blank from the first feeder, the chains of each feeder being relatively adjustable laterally of the machine.

2. In an envelope machine, in combination, a table, a feeder for accelerating a blank on the table from a state of rest, said blank having re-entrant corners in its trailing edge comprising a pair of endless chains and pins carried by the chains and engageable with the trailing edge of the blank to initiate its forward movement, said pins engaging said blank at points other than said re-entrant corners, and a timing and aligning feeder operated at a higher speed than the first mentioned feeder, and comprising a pair of endless chains and pins on the chains for overtaking the blank, engaging the trailing edge thereof gently in said re-entrant corners, and

taking over control of the blank from the first feeder, the chains of each feeder being relatively adjustable laterally of the machine, one chain of each feeder being fixed laterally of the machine, and the other chains bearing a fixed relation to one another, and being adjustable in unison laterally of the machine.

3. In an envelope machine, in combination, a table, a feeder for accelerating a blank on the table from a state of rest, said blank having re-entrant corners in its trailing edge comprising a pair of endless chains and pins carried by the chains and engageable with the trailing edge of the blank to initiate its forward movement, said pins engaging said blank at points other than said re-entrant corners, and a timing and aligning feeder operated at a higher speed than the first mentioned feeder, and comprising a pair of endless chains and pins on the chains for overtaking the blank, engaging the trailing edge thereof gently in said re-entrant corners, and taking over control of the blank from the first feeder, the chains of each feeder being relatively adjustable laterally of the machine, and driving means for the feeders constructed and arranged to maintain their operative relations to the feeders in all adjusted positions thereof.

4. The method of aligning a blank having re-entrant corners which consists in first engaging the rear edge of the blank at points spaced from said re-entrant corners and propelling the blank against frictional resistance by applying pressure at said points and then completing the alignment of the blank by engaging the re-entrant corners of the blank gently by aligning members moving at a speed slightly greater than that of the blank.

ABRAHAM NOVICK.
